UNITED STATES PATENT OFFICE.

HUGO GERNSBACK, OF NEW YORK, N. Y.

RADIO HORN.

Application filed October 27, 1923. Serial No. 537,372.

To all whom it may concern:

Be it known that I, Hugo GERNSBACK, a citizen of the United States, residing at New York city, in the county of New York and State of New York, have invented certain new and useful Improvements in a Radio Horn, of which the following is a specification.

This invention relates to acoustics and the primary object of the invention is to provide a novel horn for loud speakers of radio telephony receiving sets, which is so constructed that the distortion of the sound waves, the forming of echoes, and other extraneous noises will be effectively eliminated.

Another object of the invention is to provide an improved horn for radio telephony and telegraphy receiving sets, in which the sound waves are permitted to flow without hindrance directly from the receiver into the atmosphere, the horn serving as an effective means for amplifying the sound waves.

A further object of the invention is to provide a horn for radio receiving sets, which can be conveniently and expeditiously cast from a suitable material, such as aluminum, at a minimum cost, and which will be durable and efficient in use.

A further object of the invention is to provide novel means for associating the receiver with the horn, whereby the receiver can be easily and expeditiously connected with or removed from the horn and in which the receiver will be protected from external blows.

A still further object of the invention is to provide novel means for mounting the receiver within the horn body by a single screw and so that the diaphragm thereof will be disposed in a vertical plane and in direct alignment with the volute passageway of the horn, whereby the sound waves will be permitted to flow directly into the horn body and be amplified to a great extent.

With these and other objects in view, the invention, consists in the novel construction, arrangement and formation of parts, as will be hereinafter more specifically described, claimed and illustrated in the accompanying drawings, forming a part of this specification, in which drawings:

Figure 1 is a front elevation of the improved horn;

Figure 2 is a horizontal section through the improved horn;

Figure 3 is a vertical central section through the improved horn;

Figure 4 is a detail perspective view of the horn looking at the rear thereof.

Referring to the drawings in detail, wherein similar reference characters designate corresponding parts throughout the several views the letter A generally indicates the improved horn, which includes a sound amplifying body 5 and the attaching base 15.

The sound amplifying body 5 is of a substantial semi-spherical shape but has the upper half 6 thereof scribed on a greater arc of a circle than the lower half 7 thereof. The body in transverse horizontal cross section however is scribed on a true arc of a circle.

The outer edge of the body 5 is provided with an outwardly extending flange 8, as clearly shown in Figures 2 and 3 of the drawings.

The attaching base 15 is formed on the lower end of the body 5 and includes the outwardly and downwardly flared walls 16 which define an interior chamber 17, the purpose of which, will be hereinafter more fully described.

Extending into the body 5 from the base 15 at the forward end thereof is an inwardly extending curved lip 18, which in connection with the wall of the lower half 7 of the body 5 forms a volute passageway 10.

The lip 18 at the central portion thereof is provided with an inwardly extending concavity 19, which communicates with the chamber 17 of the base 15. This chamber or concavity 19 is shaped to conform to the configuration of the receiver B, and the receiver is adapted to fit directly within the same, and can be placed into position through the chamber 17. As shown the lip 18 is provided with an inwardly extending opening 20 for the reception of a single supporting screw 21 for the receiver B.

Thus the receiver can be held in position by means of a single retaining element. This concavity has its wall enlarged as at 22 for the reception of the usual flange on the receiver body and owing to the relation of the concavity to the volute passageway 10, the sound waves from the diaphragm of the receiver are thrown directly into this volute passageway. The wires for the receiver can be extended through the chamber 17

which can be provided with suitable outlet ways for the same if so desired.

From the foregoing description it can be seen that an improved horn has been provided for loud speakers of radio telephony and telegraphy receiving sets which will permit the sound waves to be admitted directly into the amplifying passageway of the horn and then admitted directly into the atmosphere.

Changes in details may be made without departing from the spirit or scope of this invention.

What I claim as new is:—

15 An amplifying horn for radio receiving sets comprising a substantially semi-spherical body having its outlet end disposed in a vertical plane and having its upper half

struck on a greater arc than its lower half, an outwardly directed flange formed on the 20 edge thereof, an inwardly extending lip of arcuate form in cross section disposed in the lower portion of the body forming in connection therewith a volute passageway, the lip having formed directly therein a 25 telephone receiver concavity for permitting the receiver to be disposed in a vertical plane for communication with the volute passageway, and a hollow base formed on the lower surface of the body to space the body from a support, the base having an opening therein communicating with said concavity, as and for the purpose specified.

In testimony whereof I affix my signature.

H. GERNSBACK.
